UNITED STATES PATENT OFFICE

JAMES B. ARBUCKLE, OF CHARLEROI, AND WILLIAM DEFFER, OF DONORA,
PENNSYLVANIA

WRENCH

Application filed June 1, 1928. Serial No. 282,192.

This invention has for its object the provision of a wrench which may be quickly and easily adjusted to the work upon which it is to operate and securely locked in adjustment.

5 Another object of the invention is to provide means whereby the work may be quickly released, and a further object is to provide a mounting for the relatively stationary jaw which will avoid breaking strain upon the 0 saddle or jaw support. The invention is intended more particularly for embodiment in a pipe wrench and is so illustrated but it may, of course, be embodied in a nut wrench without involving any departure from its principles. The invention is illustrated in the accompanying drawing and will be herein- 15 after fully set forth.

In the drawing:

Figure 1 is a sectional elevation of a wrench 20 embodying our present invention;

Fig. 2 is a detail perspective view of the relatively stationary jaw;

Fig. 3 is a perspective view of the saddle or main wrench body;

25 Fig. 4 is a detail of the cap which is secured over the saddle, and

Fig. 5 is a detail of the releasing trigger.

In carrying out the present invention, there is provided a wrench body or saddle 1 through 30 which the shank 2 of the adjustable jaw 3 and the shank 4 of the jaw 5 are fitted, the shank 4 being extended so as to be utilized as a lever or handle, as shown at 6 in Fig. 1. The opposed faces of the jaws 3 and 5 are formed 35 with cooperating teeth 7 which are respectively reversed and are adapted to engage opposite sides of a pipe and grip the same in the well known manner of pipe wrenches. The shank 4 is provided with an offset 8 im- 40 mediately adjacent the jaw 5 through which an opening 9 is formed to receive a pivot pin 10 inserted through the shank and corresponding openings 11 formed in the sides of the saddle. The end of the jaw 5 presented 45 to the shank 2 is also notched or recessed, as

indicated at 12, whereby it may span a slight rib 13 on the shank 2 and thereby aid in maintaining the two jaws in the proper working plane. The saddle or wrench body 1 comprises side plates connected between their ends by a partition web 14 which serves as a brace to reinforce the saddle and also as a partition to separate the shanks of the respective jaws and prevent interference between the same. A leaf spring 15 is secured to one side of the shank 4 and bears against the web 14, while a similar spring 16 is disposed at the opposite side of said shank and is secured to the end of the jaw 5 with its free end bearing against the cross web 17 which connects the reduced ends of the side plates of the saddle. These springs 15 and 16 serve to prevent actual contact between the shank or handle member and the respective webs so that the breaking strain imparted to the saddle in the ordinary pipe wrench is avoided. The springs also facilitate the desired ratchet action in the wrench whereby when moving in one direction the pipe will be engaged and when moving in the other direction the jaws will slip over the pipe without turning the same. At the end of the saddle remote from the cross web 17, the side plates thereof are connected by spaced bridges or cross blocks 18 and the shank 2 of the movable jaw is inserted between the web 14 and said end blocks or bridges. The edge of the shank 2 presented to the bridges 18 is constructed with a series of transverse teeth 19 adapted to be engaged by the locking dog 20 whereby the jaw will be locked in a set position. The dog 20 is a block of suitable size and form to fit slidably between the side plates of the saddle and between the bridging members 18 thereof, as shown clearly in Fig. 1, and it is provided with a series of teeth 21 which are adapted to interengage with the teeth 19 of the shank 2 to hold the adjustable jaw in any position in which it may be set. A headed pin or screw 22 is se- 50 55 60 65 70 75 80 85 90

cured in the locking dog which is slightly countersunk, as shown at 23, to provide a seat for an expansion spring 24 coiled around said pin or screw. A cap 25 is secured upon the bridging members 18 so as to span the same and this cap is formed with a seat 26 for the outer end of the spring 24 and with an opening 27 extending from said seat to accommodate the pin or screw 22. The cap is also provided at one end with spaced perforated lugs 28 between which is disposed the trigger 29, a pivot pin 30 being inserted through the trigger and the lugs 28 to attach the trigger to the cap. One end of the trigger is tapered, as shown at 31, and is provided with a longitudinal notch 32 adapted to engage around the pin or screw 22 beneath the head of the same, as clearly shown in Fig. 1, while the opposite end of the trigger is suitably shaped to provide a convenient thumb piece 33 which may receive pressure from the thumb or fingers of the operator without causing him any discomfort.

In assembling the parts, the shank of the relatively stationary jaw 5 is inserted through the saddle between the webs 14 and 17 and the pivot pin 10 secured in position. The locking dog 20 is engaged with the end of the pin or screw 22 after the latter has been inserted through the opening provided therefor in the cap 25, the spring 24 being placed around the pin or screw as the latter passes through the cap in an obvious manner. After the cap and dog have been assembled, the cap is placed against the bridging members 18 of the saddle, and the securing screws 34 are then driven home to secure the cap in place. The trigger is then fitted to the cap with its tapered end engaging under the pin, as shown. The shank of the adjustable jaw is then inserted through the saddle between the web 14 and the bridging members 18 and it may be pushed as far as may be desired, the spring 24 yielding and permitting the locking dog to rise as the teeth of the shank pass across the same. When the adjustable jaw has been brought to the desired position, the spring 24 will at once effect locking engagement between the dog and the shank so that the shank will be positively held against reverse movement. If it be desired to withdraw the adjustable jaw a slight pressure upon the trigger will release the dog from the jaw shank so that the jaw may then be drawn out from the saddle.

The wrench is fitted to the work by having the jaw 5 placed against the work and the jaw 3 then being adjusted in the described manner until it also engages the work. The handle is then swung toward the left in Fig. 1 of the drawing whereupon the teeth 7 of the opposed jaws will firmly bind upon and grip the work so that the work must turn with the wrench. Upon reverse force being applied to the handle, the jaw 5 will rock

slightly about its pivot 10 so that the work will be released and permit the jaws to slide around the same to obtain a fresh grip thereon. The device, consequently, will operate as a ratchet wrench, being free of the work when the handle is moved in one direction and firmly gripping the work when the handle is moved in the opposite direction. In pipe wrenches as now most generally constructed the handle impinges against the end of the saddle corresponding to the web 17 in our device and the force of the handle is transmitted to and through said element so that breakage occurs and the wrench is out of service for a greater or less period of time. With our device, this breakage is eliminated inasmuch as the spring 16 cushions the handle and prevents positive contact between the same and the web 17. Moreover, the end of the jaw 5 presented to the shank 2 is of such form that a very limited movement of the jaw 5 about its pivot is permitted and the end of said jaw is caused to lock against the shank of the adjustable jaw, whereupon the two jaws will move as a unit in turning the work. Of course, when the working stroke is completed, the pivoted jaw will release its binding engagement with the shank of the adjustable jaw to permit the return stroke without rotating the work. The locking dog whereby the adjustable jaw is held in a set position is housed within the saddle and the cap covering the same so that it is protected against chance blows which might break or otherwise damage the same while the trigger permits the dog to be easily withdrawn from the shank when the work has been turned home.

Having thus described the invention, we claim:

A wrench comprising a saddle formed with longitudinally extending passages, one passage having a side passage opening through an end of the saddle, a cap removably secured to said saddle and closing the outer end of said side passage, jaws having shanks extending through the longitudinal passages of said saddle, one shank being pivotally mounted adjacent the front of the saddle and extended rearwardly to form a handle and the other slidably through the saddle and formed with rack teeth in a side edge face facing the side passage, a locking dog as wide as the shanks are thick and substantially as long as the height of said side passage and slidable in said side passage towards and away from the toothed face of the shank and maintained longitudinally in place by the walls of the side passage and formed with teeth to engage with the teeth of the shank and to secure the shank in an adjusted position, said dog being bodily removable through the end opening of the side passage, said dog and cap being formed with aligned seats, a pin extending through the cap and engaged with

said dog and having a head at its outer end, a
spring coiled about said pin and having its
ends seated in said seats and serving to yield-
ably retain the dog in an operative position,
5 and a trigger pivoted to said cap and having
one end notched to receive said pin and
formed with a convexed outer surface bearing
against the head of the pin whereby rock-
ing of the trigger will move the pin to draw
the dog to a releasing position.

10 In testimony whereof we affix our signatures.
